US00D801990S

(12) **United States Design Patent** (10) Patent No.: **US D801,990 S**
Reissner et al. (45) Date of Patent: ** Nov. 7, 2017

(54) **DISPLAY SCREEN OR PORTION THEREOF WITH GRAPHICAL USER INTERFACE**

(71) Applicant: **Rockwell Automation Technologies, Inc.**, Mayfield Heights, OH (US)

(72) Inventors: **Kyle Reissner**, Hudson, OH (US); **Benjamin Henderson**, Chardon, OH (US); **Ashish Anand**, Mayfield Heights, OH (US); **Matthew Ericsson**, Lyndhurst, OH (US)

(73) Assignee: **Rockwell Automation Technologies, Inc.**, Mayfield Heights, OH (US)

(**) Term: **15 Years**

(21) Appl. No.: **29/583,555**

(22) Filed: **Nov. 7, 2016**

(51) LOC (10) Cl. **14-04**

(52) U.S. Cl.

USPC **D14/485**; D14/489

(58) **Field of Classification Search**

USPC D14/485-495

CPC G06F 17/211; G06F 17/212; G06F 3/1251;

G06F 3/0481; G06F 2203/04807
